(57) **CLAIM**

We claim the ornamental design for a portable diagnostic instrument protective boot, as shown and described.

DESCRIPTION

FIG. 1 is a perspective view of a portable diagnostic instrument protective boot showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of instrument and software card holding slots, body of the landscape light and base are included for the purpose of illustrating boundaries and forms no part of the claimed design.
